(57) **CLAIM**

The ornamental design of an anchor point clamp, as shown and described.

DESCRIPTION

FIG. 1 is a rear perspective view of an anchor point clamp showing our new design;

FIG. 2 is a front perspective view thereof;

FIG. 3 is a rear elevation view thereof;

FIG. 4 is a front elevation view thereof;

FIG. 5 is a first side elevation view thereof;

FIG. 6 is a second side elevation view thereof;

FIG. 7 is a top plan view thereof; and,

FIG. 8 is a bottom plan view thereof.

The features shown in broken lines in the drawing figures depict environmental subject matter only and form no part of the claimed design.
